UNITED STATES PATENT OFFICE.

SAMUEL S. RADLEY, OF GARDNER, MASSACHUSETTS, ASSIGNOR TO EVANS CASE CO., OF ATTLEBORO, MASSACHUSETTS, A CORPORATION OF MASSACHUSETTS.

LOOSE-POWDER CONTAINER.

Application filed November 3, 1925. Serial No. 66,673.

My invention relates to a container for loose powder and adapted to be embodied for example in a vanity case or in a container adapted for holding other materials 5 in the form of a loose powder. The invention particularly relates to that form of powder container in which the powder is held about a member having a central opening to which powder may be directed by the 10 depression of a diaphragm normally closing the opening.

The general object of my invention is to provide a loose powder container including a member having an opening to afford access 15 to the powder and in which the diaphragm forming a closure of said opening is provided in a simple manner whereby the number of parts constituting the container is greatly reduced and the construction greatly 20 simplified. The invention also has for an object to provide a container of the indicated character in which the powder will be directed unfailingly to the area of the diaphragm at the opening referred to as well as 25 to provide novel means to prevent caking of the material in the container.

The nature of my invention, its distinguishing features and advantages will clearly appear as the description proceeds.

Reference is to be had to the accompanying drawings forming a part of this specification, it being understood that the drawings are merely illustrative of one example of the invention.

Figure 1 is a vertical section of a loose powder container embodying my invention; Figure 2 is a plan view thereof.

In carrying out my invention a box body designated generally by the numeral 10 is provided having a bottom 11 and a side flange 12. In practice, the upper edge of the side flange 12 is directed laterally inward as at 13. In association with the container body 10 I provide a powder-retaining element 14 in the form of a cover having a central opening 15 at which the powder A held in the container may be accessible. The central opening 15 is below the top of the element 14 and the bottom of said element 45 is convergent toward said opening. The element 14 at the top has a cylindrical zone 16 at the upper edge of which is an annular flange 17 directed laterally outward and seating on the seat provided by the upper

edge of the body flange 12 and its inwardly 55 directed annular portion 13.

The bottom 11 for its major portion constitutes a diaphragm 18 which is made somewhat concavo-convex, the inherent resiliency of the diaphragm 18 serving to effect 60 a closure of the opening 15. Said opening is defined by a downwardly directed edge 19 with which the diaphragm 18 has edge contact.

The powder A is contained in the body 65 10 beneath the closure element or cover element 14 so that the mass of powder is held in annular form about the opening 15 and is held from escaping by reason of the contact of the diaphragm 18 with the cover element 14 at the edge portion 19. It will be obvious that upon pressure being applied to the diaphragm 18 at its upper surface, said diaphragm will be depressed, thereby 70 serving to break the contact between said 75 diaphragm 18 and the edge portion 19 of the cover element. Hence, a shaking of the container will cause some of the powder A to sift past the edge 19 to distribute itself over the exposed central area of the diaphragm 18 so that the powder at said exposed portion on the diaphragm will be 80 readily accessible through the opening 15 to be picked up by a powder puff, chamois, or the like, for example, or otherwise utilized.

I provide novel means of preventing the caking of the powder A so that it may always be relied upon to sift to the opening 15 upon the depression of diaphragm 18. The means for the purpose is in the form 90 of an agitator ring 20 extending about in the powder-containing compartment and of a size sufficiently larger than the annular edge 19 to permit of the ring 20 moving about the container body 10 upon the shaking of the latter. Thus, a slight shaking of the box 10 will overcome any tendency of the powder A to solidify or cake.

The bottom 11 has an annular corrugation 21 within which the ring 20 is held, said corrugation thus constituting a strengthening of the bottom as well as lending resiliency to the diaphragm 18 and at the same time serving to limit the movement of the ring 20.

It is to be observed that the described construction provides a container made of two pieces, that is to say, the box body 10 and the cover element 14, the only other element

involved in the construction being the power stirring ring 20 the advantage in employing which is apparent. It is to be observed also that the bottom 11 of the container body 5 forms the diaphragm 18 to close the opening 15, thereby avoiding the employment of a separate diaphragm for the purpose.

I would state in conclusion that while the illustrated example constitutes a practical 10 embodiment of my invention, I do not limit myself strictly to the exact details herein illustrated, since, manifestly, the same can be considerably varied without departure 15 from the spirit of the invention as defined in the appended claims.

Having thus described my invention, I claim:

1. A loose powder container comprising a body and a cover having an opening exposing the bottom of the body, said bottom of the body being in the form of a diaphragm closing said opening, the container outside 20 of said opening and beneath the cover element forming a compartment for powder 25 and the depression of the diaphragm serving to permit escape of the powder to the opening.

2. A loose powder container comprising a body and a part forming a cover and presenting an opening, the body beneath the 30 cover part forming the container for powder

extending about said opening, the bottom of the body constituting a diaphragm forming a closure for said opening and depressible to permit powder to escape to the diaphragm at 35 the opening.

3. A loose powder container comprising a body composed of a bottom and side flange, and an element forming a cover for said body and resting on said flange, said 40 cover element presenting an opening and the bottom of the body constituting a diaphragm in edge contact with the cover element at said opening.

4. A loose powder container comprising a body and a cover having an opening exposing the bottom of the body, said bottom at the central portion being in the form of a resilient diaphragm closing said opening and depressible, the body beneath the cover 50 element forming a container for powder which may escape upon the depression of the diaphragm.

5. A powder container comprising a body, a cover element having an approximately 55 central opening, the bottom of the body forming a depressible diaphragm, the body beneath the container forming an annular powder compartment, and a ring loose in the body in said compartment to agitate the 60 powder.

SAMUEL S. RADLEY.
